DELIVERY SLIDE FOR LINOTYPE MACHINES

Emil Szubzda, New Bedford, Mass.

Application October 11, 1946, Serial No. 702,637

4 Claims. (Cl. 308—3)

1

The present invention relates to new and useful improvements in typographical machines, and more particularly, to a self-adjusting sliding block for the line delivery slide of the machine.

An important object of the invention is to provide a sliding block including means for creating a steady, gentle pressure at the upper and lower edges of the block in the guide grooves to provide the required friction for the proper operation of the machine.

The present delivery slides for the long fingers of typographical machines wear out very rapidly at the beveled edges of the block due to the fact that the side friction shoe presses against one side of the groove and face of the block, thus causing uneven wear and throwing the sliding block out of alignment with other parts of the machine and resulting in poor service, waste of time and expense for replacement.

Accordingly, it is an object of the present invention to provide a sliding block for the delivery slide of machines of this character which overcomes the objectionable features usually found in conventional sliding blocks.

A further object of the invention is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is an end elevational view of the sliding block.

Figure 2 is a side elevational view thereof.

Figure 3 is a vertical sectional view taken on a line 3—3 of Figure 2.

Referring now to the drawings in detail, wherein for the purpose of illustration I have disclosed a preferred embodiment of the invention, the numeral 5 designates a sliding block generally which is composed of upper and lower block sections 6 and 7, the upper edge of the upper section 6 being beveled, as shown at 8, for riding in the upper groove 9 for the delivery slide, and the lower edge of the lower section 7 is also beveled, as shown at 10, for riding in the lower groove 11 of the delivery slide.

A plurality of rods 12 have their upper ends suitably secured in the upper section 6 of the block and have their lower ends freely positioned

2

in bores 13 extending vertically in the lower section 7 of the block. The lower ends of the rods project into the beveled sides 10 of the lower section 7 and the lower ends of the rods are correspondingly beveled, as shown at 14, and are exposed at beveled surfaces 10 of the blocks.

Coil springs 15 are mounted on the rods 12 between the adjacent edges of the sections 6 and 7 of the block and exert their tension on the blocks to spread the blocks apart to provide a proper frictional engagement between the beveled edges 8 and 10 and the respective grooves 9 and 11.

A pair of adjustable stops 16 are secured to one side of the lower section 7 of the block, the stops including a vertical slot 17 in which a set screw 18 carried by the lower section of the block is received for securing the stops in vertically adjusted position, the upper end of the stop having an inwardly projecting flange 19 underlying the lower edge of the upper section 6 of the block. The flange 19 of the stop is set at an adjustment to space the lower edge of the upper section 6 of the block at three-thousandths or four-thousandths of an inch therefrom.

The upper section 6 of the block carries the long fingers 20 of the line delivery slide for operation in the usual manner.

The springs 15 function to automatically adjust the sections 6 and 7 of the blocks in the grooves 9 and 11 to compensate for wear in the grooves and maintain the blocks in proper alignment in the delivery slide.

It is believed that the details of construction, manner of use and advantages of the device will be readily understood from the foregoing without further detailed explanation.

It is to be understood, however, that even though I have herein shown and described a preferred embodiment of my invention, the same is susceptible of certain changes fully comprehended by the spirit of the invention as herein described, and the scope of the appended claims.

Having thus described my invention, what I claim is:

1. A type delivery slide block for a typographical machine comprising a first block section having one edge beveled to fit a delivery slide groove and its opposite edge substantially flat and having spaced apart bores extending substantially perpendicular to said flat edge, a second block section having one edge beveled to fit a delivery slide groove and its opposite edge substantially flat and having spaced apart bores extending substantially perpendicular to its flat edge, said

block sections being spaced apart at their flat edges when operatively assembled with a delivery slide, pins secured one in each bore of one of said block sections and slidably received in corresponding bores of the other block section, and compression springs disposed between the flat edges of said block sections and respectively surrounding said pins to resiliently urge the beveled edges of said block sections into frictional engagement with the surfaces of corresponding delivery slide grooves.

2. A type delivery slide block for a typographical machine comprising a first block section having one edge double beveled to fit a delivery slide groove and its opposite edge substantially flat and having spaced apart bores extending therethrough substantially perpendicular to said flat edge, a second block section having one edge double beveled to fit a delivery slide groove and its opposite edge substantially flat and having spaced apart bores extending therethrough substantially perpendicular to said flat edge, said block sections being spaced apart at their flat edges when operatively assembled with a delivery slide, pins secured one in each bore of one of said block sections and slidably received in corresponding bores of the other block section, and compression springs respectively surrounding said pins between the flat edges of said block sections to resiliently urge the beveled edges of said block sections into frictional engagement with the surfaces of delivery slide grooves, said pins having a length substantially equal to the distance between the bottoms of opposed delivery slide grooves and having their ends beveled to fit such grooves.

3. A type delivery slide block for a typographical machine comprising a first block section having its upper edge beveled to fit a delivery slide groove and its opposite edge substantially flat and having spaced apart bores extending therethrough substantially perpendicular to said flat edge, a second block section having one edge beveled to fit a delivery slide groove and its opposite edge flat and having spaced apart bores extending therethrough substantially perpendicular to said flat edge, said block sections being spaced

5 apart at their flat edges when operatively assembled with a delivery slide, pins secured one in each bore of one of said block sections and slidably received in corresponding bores of the other block section, compression springs disposed between the flat edges of said block sections and respectively surrounding said pins to resiliently urge said block sections apart, and stops adjustably secured to one of said block sections and 10 extending across the space between said block sections to underlie the flat edge of the other of said block sections and provide a limit stop for relative movement of said block sections toward each other.

15 4. A type delivery slide block for a typographical machine comprising a first block section having one edge beveled to fit a delivery slide groove and its opposite edge flat and having spaced apart bores extending therethrough substantially perpendicular to said flat edge, a second block section having one edge beveled to fit a delivery slide groove and its opposite edge flat and having spaced apart bores extending therethrough substantially perpendicular to its flat edge, said block sections being spaced apart at their flat edges when operatively assembled with a delivery slide, pins secured one in each bore of one of said block sections and slidably received in corresponding bores of the other block section, and resilient 20 means disposed between said block sections and bearing against the opposed flat edges of both of said sections to urge said block sections relatively away from each other and into frictional engagement with the surfaces of opposed delivery slide grooves.
